(57) **CLAIM**

The ornamental design for an “accessory for a tap” as shown and described.

DESCRIPTION

FIG. 1 is a perspective view of an accessory for a tap.

FIG. 2 is a top plan view of the accessory of FIG. 1.

FIG. 3 is a bottom view of the accessory of FIG. 1.

FIG. 4 is a front view of the accessory of FIG. 1.

FIG. 5 is a rear view of the accessory of FIG. 1.

FIG. 6 is a right side view of the accessory of FIG. 1; and, FIG. 7 is a left side view of the accessory of FIG. 1.

The lighter solid lines denote surfaces and contours. Line shading is not surface ornamentation.

The features shown in broken lines form no part of the claimed design.
